LOOSE-LEAF BINDER

Sheldon Van Buren, Chicago, Ill.

Application July 29, 1940, Serial No. 348,147

9 Claims. (Cl. 129—35)

This invention relates to loose-leaf binders or holders and is an improvement upon the device shown in the patent to Clyde V. Van Buren, No. 1,869,032, dated July 26, 1932.

The primary reason for these improvements, and conversely, the main disadvantage of the previous invention, was that in engaging or releasing the paper the spring was slid against the top sheet. This either marked, wrinkled, or tore the top sheet, rendering the device undesirable to many. Therefore, my problem was to find a construction that forced the spring pressure vertically onto the paper and eliminate the lateral or longitudinal sliding necessary to engage the contents such as required by the other device.

Another object of the invention is to provide a device of the above character which is simple and inexpensive and which will hold single leaves or piles thereof of various thicknesses and in which the parts are permanently retained in assembled relation instead of being detachable.

A further object of the invention is to provide a loose leaf binder or holder which facilitates the insertion of the sheets, especially where the thicknesses of the sheets or leaves is such as to employ the full capacity of the binder or substantially so and to facilitate manufacture and assemblage of the parts of the device as well as to strengthen the same and facilitate the insertion and clamping of the sheets.

Another object of the invention is to reinforce the upper flange portions of the channel forming the receptacle for the marginal portions of the sheets to be held; to mount the bowed spring clamping element so that it will not become displaced and so as to allow free swinging movement thereof in a small arc when near the capacity holding point and to provide a slide which will release the clamping element or move and positively hold the clamping element in clamping position and permit automatic adjustment of the clamping element to the thicknesses of the sheets held thereby.

Further objects and advantages will appear and be brought out more fully in the following specification, reference being had to the accompanying drawing, in which:

Fig. 1 is a perspective view of a loose leaf binder equipped with a holding device in accordance with the invention;

Fig. 2 is an enlarged longitudinal section taken on the line 2—2 of Fig. 1;

Fig. 3 is a fragmentary enlarged section similar to Fig. 2;

Fig. 4 is a fragmentary plan view showing the locking slide and with the binder in section.

Fig. 5 is a longitudinal section taken on the line 5—5 of Fig. 4; and

Figs. 6 and 7 are transverse sectional views taken on the lines 6—6 and 7—7 of Fig. 4.

The invention comprehends broadly the utilization of a holder for receiving the marginal portions of the sheets and having a spring tongue which is swingably mounted at one end and releasably held at its opposite end, the intermediate portion of the tongue or clamping element being bowed so as to accommodate itself conformably to different thicknesses of the sheets or leaves clamped thereby and the holder may be used by itself or in connection with a cover or binder. As shown, the device may be provided or employed as a loose leaf holder to releasably hold sheets by itself or in connection with an ordinary type of loose leaf binder, cover or folder shown as comprising the backing boards 10 and 11, 10 being the bottom board or folder and 11 being the top board or cover, which are hingedly attached or scored at 12 and 13 along the opposite edges of a binding 14.

The holding device comprises an angle member or channel 15 of suitable strength or rigidity, such as cold rolled steel or other sheet material of metal, plastic, of Bakelite, fiber or the like and having a lower flange 16 and an upper flange 17 connected by a back portion 18. The bottom portion or flange 16 is suitably attached to the binder or folder and is shown provided with two openings preferably offset downwardly in the form of a countersink to receive rivets 19 therethrough and through the bottom board 10 so that the rivets will lie flush with the top surface of the lower flange 16 so as not to mutilate the sheets, especially the bottom sheet and to firmly attach the holder to the binder, although as previously stated, it may be used without the binder or folder. The upper or top flange 17 is provided with an elongated longitudinal slot 20 located equi-distantly between the ends thereof to provide imperforate end flanges and guide rails or strips 21 and 22 along opposite sides of the slot over the lower or horizontal leg and projecting out from the vertical leg or back of the holder.

A spring clamping tongue or element 23 of such a width as to readily pass through the slot 20 with clearance on both sides, has an angular end 24 disposed beneath the top flange adjacent the end of the slot and this angular portion is provided with an aperture 25 at the angle or bend 55

which is of obtuse-angled shape, as shown. A rivet 26 is passed through the aperture in the tongue and also through a corresponding aperture in the top flange adjacent the end of the slot 20 to pivotally or swingably mount the spring clamping tongue so that it may have free swinging movement through a small arc riding on the top of the angular portion 28 so that the free end of the spring will project up through the slot and the portion adjacent the anchored end will move in close proximity to the top flange so as to facilitate the insertion of the sheets to be held up to the capacity of the channel determined by the width of the space between the top and bottom flanges. The rivet 26 which is passed through the apertures in the tongue and top flange 17, is upset as indicated at 27 to retain the tongue in position and still mount the same loosely instead of clamping the spring tight so as to permit the spring to swing freely in a limited arc as previously described.

The free end of the spring is bent angularly at an obtuse angle as indicated at 28 so that when located beneath the top flange it will incline downwardly to prevent the free end thereof from engaging with a slide 29 which is mounted at the slot 20 to move along the guideways or rails formed by the strips 21 and 22. This slide comprises a plate 30 of similar sheet metal having opposite side extensions 31 and 32 which overlie the top faces of the strips 21 and 22 to bear thereon and slidably mount the plate. The inner end 33 of the plate forming the slide is bent downwardly as at 34 the thickness of the strips 21 and 22 so that the portion 33 is disposed between or below said strips and one end has an extension wing 35 which extends beneath the strip 21 to prevent upward displacement of the slide. The opposite end of the plate 30 has an extension 36 with cut-outs or recesses 37 extending inwardly in opposite directions and in transverse alignment at its juncture with the plate 30 and the opposite edges of the extension or end portion 36 are bent down in angular relation as at 38 along the inner edges of the strips 21 and 22 and then outwardly beneath said strips at 39 and 40 to engage the bottom faces of the strips similar to the wing portion 35 so as to slidably mount the plate on the strips 21 and 22 and retain the slide in position between the same and the opposite extensions 31 and 32. In this manner, the slide is retained in position because the extension wings engage on opposite sides of the strips 21 and 22 so that the slide may be freely moved along the guideways to move over the angular end 28 which will ride between the wings 39 and 40 in the channel or groove provided therebetween and thus move the clamping member or spring normally in clamping engagement with the sheets S which are fitted at their marginal portions in the channel between the flanges thereof, irrespective of the number of sheets and the thickness of the sheets thus held. Thus, one end of the spring tongue is loosely pivoted beneath the flange 17 and the other end is inserted under the opposite portion of the flange 17 in releasable engagement beneath the slide by movement in the slot 20 which while permitting limited lateral movement or play of the spring tongue between the strips 21 and 22, will prevent the spring tongue from becoming loose, displaced or lost as in the prior construction. By sliding the plate 30 along the slot on the guideways or rails formed by the strips 21 and 22, it will frictionally engage the free end of the

spring tongue and normally press it down causing the spring to flex and adjust itself conformably to the thickness of the sheets held by the binder. The greater the thickness the more the spring will flex or move toward a rectilinear position as seen in full lines in Fig. 2 of the drawing. In this position, the slide 29 will be at the extreme upper or right hand end of the slot 20 so as to confine the angular free end of the spring tongue therebeneath held against lateral displacement or movement as described. However, when the slide is moved toward the opposite end as indicated in dotted lines in Fig. 2, pressure thereof against the spring tongue will be released permitting the free end of the spring to normally move upwardly to the dotted line position shown in Fig. 2 to release the pressure on the sheets so that the same may be withdrawn or additional sheets inserted. From this position in which the spring tongue springs upwardly under its own tension or in conjunction with the pressure of the sheets held thereby, the spring tongue is loosely mounted to swing freely upwardly in a limited arc as seen in Fig. 3 so that the upward projection of the free end of the spring tongue will be greater and the anchored end of the spring tongue will move in closer proximity to the upper flange and the slide, thus facilitating the insertion of sheets of considerable thickness approximating that of the space between the top and bottom flanges of the holding device.

In order to facilitate movement of the slide, the latter is provided with two sets of slotted vanes 41 and 42 projecting in opposite directions and spaced apart to form roughened or knurled finger engaging portions by which the slide may be pushed, especially in frictionally engaging or disengaging the angular free end of the spring tongue in clamping or releasing the sheets. This is particularly true due to the fact that the spring tongue is bowed with a considerable degree of curvature as shown in dotted lines in Fig. 2 of the drawing so that when its free end portion is engaged beneath the slide by moving the latter to the end of the slot 20 over the free end of the spring tongue, the middle portion of the tongue engages the bottom flange 16 of the angle or channel member 15 and is flattened somewhat, thereby creating considerable tension in the fastened tongue. In this way, the tongue is adapted to clamp and securely hold different thicknesses ranging from a single sheet to a pile of sheets of a thickness that will fit between the upper and lower flanges of the channel or angle member of the holding device. By mounting the spring tongue as described, instead of in the manner shown in the patent referred to, the spring tongue is permanently attached instead of being removably mounted and will be prevented from becoming displaced or separated from the remaining structure of the holding device and possibly lost. This is due to the fact that the parts are always securely held in assembled relation even though the slide is freely movable to press the spring tongue in engaging position to clamp the sheets or to release the same for removing or inserting any or all of the sheets or additional ones as will be found necessary or desirable in practice.

In the structure shown in the drawing, the angle member or channel 15 of the holding device which is riveted through the lower flange 16 to the bottom board 10 of the folder or binder, is exposed throughout, but obviously, with the ex-

ception of the upper flanges or flange portions and the spring tongue which cooperates therewith, the device may be imbedded within the component makeup of the boards 10 and 11 and the 5 backing or binding 14.

Thus, it will be seen that instead of loosely or slidably mounting the spring clamping tongue or element in the receptacle formed by the angle member or channel as in the prior patent here- 10 tofore referred to, so that in engaging or releasing the paper the spring was slid against the top sheet so as to mark, wrinkle or tear the same and render the device objectionable and un- 15 desirable to many, the spring clamping tongue or element is free to move up and down, the spring pressure or force acting in a vertical direction against the paper and eliminating the lateral or longitudinal sliding required and necessary to engage the paper or contents of the 20 holder due to the loose slidable mounting of the spring tongue in the old construction. This also facilitates the insertion and removal of the contents or sheets and insures that the same will be maintained in a smooth condition and not mutilated, wrinkled or torn.

It is further obvious that many other modifications in the structure of the holding device and its particular application in use may be made without in the least departing from the spirit 30 and scope of the invention as defined by the appended claims. The invention, therefore, is not limited to the specific construction and arrangement shown in the accompanying drawing.

Having thus described my invention, what I 35 claim is new and desire to secure by Letters Patent is:

1. A loose-leaf holder comprising an open-sided receptacle for the marginal portions of the leaves to be held, one side of said receptacle 40 having a longitudinal slot and a normally bowed spring clamping element permanently and swingably supported at one end beneath said side for movement through the slot and detachably engageable at its opposite end beneath a top member of the receptacle displaceable in the slot in cooperative clamping relation to different thicknesses of leaves in said receptacle.

2. A loose-leaf holder comprising an open-sided receptacle for the marginal portions of the 50 sheets to be held, one side of said receptacle comprising spaced flanges, a normally bowed spring clamping element permanently and swingably supported at one end on one of said flanges and a slide movably carried by said side of the 55 receptacle and detachably engageable with the opposite free end of the spring clamping element in a plane substantially under the other flange by movement of the slide over said free end to hold the spring clamping element in cooperative 60 clamping relation to different thicknesses of sheets in said receptacle or inwardly of said free end to release the spring clamping element from clamping relation with the sheets.

3. A loose-leaf holder comprising an open-sided receptacle for the reception of the marginal portions of the sheets to be held, one side of said receptacle having a longitudinal slot, a normally bowed spring clamping element loosely riveted 65 beneath said side beyond one end of the slot and adapted to swing freely through a limited arc, and a slide guided along said side at the slot to engage over the free end of the clamping element and hold the same in clamping relation to the 70 sheets in said receptacle.

4. A loose-leaf holder comprising an open-sided receptacle for the marginal portions of the sheets to be held, one side of said receptacle having a longitudinal slot with opposed strips, a normally bowed spring clamping element per- 5 manently and swingably attached to said side beyond one end of the slot and bowed down- wardly toward the other side of the receptacle, and a slide movable in the slot along the strips to engage over the free end of the spring clamp- 10 ing element and press the same in flexing relation conformable to the sheets held in the recep- tacle.

5. A loose-leaf holder comprising an open-sided receptacle in the form of a channel and 15 adapted to be secured in a folder, said receptacle adapted to receive the marginal portions of the sheets to be held and having a top portion with a confined longitudinal slot and guide rails, a normally bowed spring clamping element having 20 an angular end riveted through one side of the receptacle beyond the one end of the slot and having an angular portion adapted to swing freely through a small arc beneath the said side of the receptacle and an angular free end with 25 the intermediate bowed portion movable through the slot and extending down in clamping relation toward the other side of the receptacle and the sheets in said receptacle, and a movable member mounted on the guide rails at the slot to move 30 over the free end of the clamping element in the area of the slot to hold the element in clamping position or to uncover said free end and release the element for upward movement through the slot out of clamping relation with the sheets. 35

6. A loose-leaf holder comprising an open-sided receptacle in the form of a channel and adapted to be secured in a folder, said receptacle adapted to receive the marginal portions of the sheets to be held and having a top portion with 40 a confined longitudinal slot and guide rails, a normally bowed spring clamping element having an angular end riveted through one side of the receptacle beyond the one end of the slot and having an angular portion adapted to swing 45 freely through a small arc beneath the said side of the receptacle and an angular free end with the intermediate bowed portion movable through the slot and extending down in clamping relation toward the other side of the receptacle and the 50 sheets in said receptacle, and a movable member mounted on the guide rails at the slot to move over the free end of the clamping element in the area of the slot to hold the element in clamping position or to uncover said free end and release 55 the element for upward movement through the slot out of clamping relation with the sheets, said movable member having opposite extensions overlying the guide rails on opposite sides thereof to retain the movable member in position and having means to confine the free end of the clamping element therebetween and a roughened manipulating portion. 60

7. In a loose-leaf binder, an open-sided recep- 65 tacle having a top flange provided with an elongated opening, a bow spring clamping element permanently and swingably anchored near one end to the top flange beyond the opening, bowed downwardly intermediately and having its free 70 end terminating adjacent the opposite end of the opening to swing up and down through the latter, and a member movably mounted on the top flange at opposite sides of the opening to engage over the free end of the element to hold 75

the latter in clamping relation to sheets held in the receptacle or uncover said end to release the element and sheets.

8. A loose-leaf binder comprising a channel adapted to be secured to a folder, the top flange having a slot and strips along the sides thereof, a bow spring having an angular end loosely riveted through the top flange to swing vertically through the slot in a limited arc, the free end 10 of the spring being angularly bent and a slide movable in the slot and having portions engaging above and below the strips to secure the slide in position for movement over the free end of the spring, to force the spring in clamping relation

to marginal portions of sheets disposed in the channel.

9. A loose-leaf holder comprising an open-sided receptacle for the reception of the marginal portions of the sheets to be held, one side 5 of said receptacle having a longitudinal slot, a normally bowed spring clamping element loosely mounted beneath said side beyond one end of the slot and adapted to move freely through said slot in a limited arc, and a slide guided along 10 said side at the slot to engage over the free end of the clamping element and hold the same in clamping relation to the sheets in said receptacle.

SHELDON VAN BUREN.
